[57] CLAIM

The ornamental design for a compact disc storage and display rack, as shown and described.

DESCRIPTION

FIG. 1 is a perspective view of a compact disc storage and display rack showing our new design;

FIG. 2 is a top plan view thereof;

FIG. 3 is a bottom plan view thereof;

FIG. 4 is a right hand end elevational view thereof;

FIG. 5 is a left hand end elevational view thereof;

FIG. 6 is a side elevational view thereof, the opposite side being a mirror image thereof; and,

FIG. 7 is a sectional view taken on line 7—7, FIG. 2.

FIG-2

FIG-3
